Primary Examiner — Joseph Kukella*Assistant Examiner* — Lavon M. Amerson(57) **CLAIM**

The ornamental design for a vehicle rack as shown and described.

DESCRIPTION

FIG. 1 is a perspective view of the vehicle rack showing my new design.

FIG. 2 is an additional perspective view of a FIG. 1.

FIG. 3 is a side elevational view of FIG. 1.

FIG. 4 is a front elevational view of FIG. 1.

FIG. 5 is a top elevational view of FIG. 1.

FIG. 6 is a side elevational view of FIG. 1.

FIG. 7 is a back elevational view of FIG. 1; and,

FIG. 8 is a bottom elevational view of FIG. 1.

In the drawings, the broken line(s) define the bounds of the claimed design and form no part thereof.

1 Claim, 6 Drawing Sheets(56)
